UNITED STATES PATENT OFFICE.

WILLIAM G. CANION, OF EL PASO, TEXAS, ASSIGNOR TO ARIZONA AUTOMATIC AIR ASSOCIATION, OF BISBEE, ARIZONA, A CORPORATION OF ARIZONA.

EMERGENCY BRAKE-SETTING APPARATUS FOR ELEVATORS.

1,095,958.

Specification of Letters Patent.

Patented May 5, 1914.

Application filed June 10, 1913. Serial No. 772,831.

To all whom it may concern:

Be it known that I, WILLIAM G. CANION, a citizen of the United States, residing at El Paso, in the county of El Paso and State of Texas, have invented new and useful Improvements in Emergency Brake-Setting Apparatus for Elevators, of which the following is a specification.

This invention is an improved emergency brake setting apparatus for elevators, especially for the type of elevators used in mines, the object of the invention being to provide an improved apparatus of this character for operating the controlling element of the car or cage carried brake apparatus to move such controlling element to brake applying position in an emergency and which setting apparatus may be controlled automatically by a speed governor of the hoisting apparatus and may also be manually set in operation by the engineer or attendant at the hoisting apparatus and thus cause the brakes to be applied and the car prevented from falling in the event that the cable should break or slip or that the hoisting apparatus should race or other accidents occur.

Another object is to provide an improved fluid pressure actuated apparatus arranged at one side of the path of the car or cage and having a setting element movable into the path of the controlling element of the car carried brake apparatus to move the said controlling element to brake applying position in the event of an accident.

Another object is to provide a series of such fluid pressure actuated mechanisms and a common controlling element therefor to cause the setting elements of all of said fluid pressure actuated mechanisms to be simultaneously projected into the path of the controlling element of the car carried brake apparatus so that it will be certain that the controlling element of the brake apparatus will be moved to brake applying position by one of said fluid pressure actuated mechanisms.

With the above and other objects in view the invention consists in the construction,

combination and arrangement of devices hereinafter described and claimed.

In the accompanying drawings: Figure 1 is an elevation of an elevator car or cage, a hoisting mechanism therefor and an emergency brake setting apparatus constructed in accordance with my invention, the shaft of a mine in which the elevator operates being indicated in section. Fig. 2 is an inverted plan of the elevator car showing the compressed air brake apparatus thereof and also showing my improved emergency setting apparatus in operative connection therewith, the guides between which the car travels in its vertical movement being indicated in section. Fig. 3 is an enlarged detail vertical central sectional view of a member of the series of my improved emergency brake setting apparatus showing the construction of the cylinder and piston thereof in detail. Fig. 4 is a vertical sectional view of the same on the plane indicated on the line *a-a* of Fig. 3. Fig. 5 is a similar view indicated by the line *b-b* of Fig. 3. Fig. 6 is an end elevation of the same.

For the purposes of this specification the guides in a mining shaft are indicated at 1, the elevator car or cage at 2 provided with shoes 3 which engage the said guides and an air brake apparatus is indicated on the bottom of and carried by the car, such air brake apparatus including a cylinder 4 a reservoir 5 connected to the cylinder through a pipe 6 at the rear end of the cylinder and an intermediate pipe 7 arranged at a point near the center of the cylinder and provided with a check valve 8 to close against the back pressure from the cylinder, a brake shoe 9 operated by a piston in the cylinder and a reduction pipe 10 leading from the front end of the cylinder and provided with an emergency valve 11 and a controlling lever 12 connected to the said emergency valve and arranged to open the latter when the outer end of the said controlling lever is raised.

Within the scope of my invention any suitable type of car carried brake apparatus

may be employed it being essential however that such apparatus be provided with a con-
direction causes the brakes to be applied.
trolling element which when moved in one
5 In accordance with my invention I provide
a fluid pressure actuated mechanism includ-
ing a cylinder 13 and a piston 14 having a
rod 15 provided at its outer end with a
suitable tappet 16. In practice the cylinder
10 is provided at points intermediate its ends
with bleeding grooves or bypasses 17 to
equalize pressure and cause the piston to
normally remain in retracted position near
the rear end of the cylinder and engaged by
15 a stop screw 18. A cap or head 19 is
also in practice screwed to the front end
of the cylinder and is provided with a
packing box 20 in which a gland or sleeve
21 is threaded and through the bore of
20 which the piston rod extends. A cap 22
is threaded to the rear end of the cylin-
der to close the same and form an exten-
sion thereof and the cap is provided with
an angular wrench engaging portion 23.
25 Any suitable number of such fluid pressure
actuated mechanisms may be employed and
in practice I arrange them at one side of the
path of the car in the shaft and at points ap-
proximately 30 feet apart, from the mouth
30 of the shaft to its bottom, the number of
such fluid pressure actuated mechanisms
employed being dependent upon the depth
of the shaft. These fluid pressure actuated
mechanisms are connected together by a ver-
35 tically arranged pipe 24 which is common
to all of such mechanisms and through
which they are charged with compressed air
and by means of which the compressed air
may be discharged from the front ends of
40 their cylinders to reduce pressure on the
front sides of the pistons and hence cause
them to be moved outwardly or forwardly
by the compressed air behind them so as to
simultaneously project the tappet 16 of the
45 piston rods 15 into one side of the shaft and
in the path of the controlling element 12 of
the car carried brake apparatus.
At the upper end of the pipe 24 is a re-
duction valve 25 having a control lever 26
50 arranged to be operated by the governor 27
of the hoisting apparatus 28, and the said
pipe 24 is also provided with a reduction
valve 29 having a manually operated lever
30 which may be used by the engineer or at-
tendant to simultaneously reduce the pres-
sure in the front ends of all the cylinders in
the event of an accident, and thus cause all
the pistons to be projected and their tap-
55 pets to be arranged in the path of the con-
trolling element or lever 12 of the car car-
ried brake apparatus and thus cause the
brakes to be set and prevent the car from
dropping.

For the purposes of this specification the

hoisting apparatus 28 is illustrated as of 65
ordinary type and the governor 27 is illus-
trated as of the centrifugal type geared to
the shaft 30' of the hoisting apparatus by
gears 31, 32, shafts 33, 34 and gears 35, 36,
37 and 38. Within the scope of my inven- 70
tion the governor and the hoisting appara-
tus may be of any suitable type or construc-
tion.

In the event that any accident should occur 75
which would cause the hoisting apparatus
to race the governor will automatically
turn the lever 26 of the valve 25 and hence
open said valve and thereby reduce the pres-
sure in the front ends of the cylinders 13 80
and cause the tappet elements 16 to be pro-
jected. As the car moves past one of the
cylinders 13 the projected tappet element 16
of such cylinder will catch the controlling
element 12 of the car carried brake appara- 85
tus and turn such element to the angle re-
quired to cause said brake apparatus to op-
erate and apply the brakes thereby stopping
the car. Should the tappet element of one
cylinder fail to operate the controlling ele- 90
ment 12 the said controlling element would
be engaged and operated by the tappet ele-
ment of the next cylinder and since a num-
ber of such cylinders are employed the ap-
plication of the brakes and the prevention 95
of an accident such as the dropping of a car
will be assured.

I claim:

1. In an elevator, the combination of a car carried brake apparatus having a movable controlling element and a series of fluid pressure actuated mechanisms disconnected from the car and having a common controlling element, each fluid pressure actuated mechanism also having a setting element movable into the path of the controlling ele- 105
ment of the brake apparatus.

2. In an elevator, the combination of a car carried brake apparatus having a movable controlling element, a fluid pressure actuated apparatus having a setting element movable into the path of the controlling ele- 110
ment of the brake apparatus, a controlling element for said fluid pressure actuated apparatus a hoisting apparatus for the car, and a governor arranged to automatically 115
operate the controlling element of the fluid pressure actuated apparatus.

3. In an elevator, the combination of a car carried brake apparatus having a movable controlling element, a series of fluid pressure actuated mechanisms each having a setting element movable into the path of the controlling element of the brake appa- 120
ratus, a common reduction pipe for the said series of fluid pressure actuated mechanisms, 125
a manually operated valve for said common reduction pipe and a governor controlled valve for said common reduction pipe.

4. In an elevator, the combination of a car carried brake apparatus having a movable controlling element, a series of spaced fluid pressure actuated mechanisms, disconnected from the car and each having a setting element movable into the path of the controlling element of the brake apparatus, and a common charging and reduction

pipe for said fluid pressure actuated mechanisms.

In testimony whereof I affix my signature in presence of two witnesses.

10
